UNITED STATES PATENT OFFICE

ORLANDO M. CARSE, OF MAPLE HEIGHTS, OHIO

APRON FOR CAR DUMPERS

Application filed May 5, 1930. Serial No. 449,738.

This invention relates to car dumpers, and particularly to those having a cradle which is adapted to be tilted for emptying the contents of the car. To obtain complete emptying of the car, it is usually necessary to turn it about 160 degrees. In elevating car dumpers, the material starts to leave the car however, when the tilting operation has progressed about 45 degrees, and then moves with considerable rapidity when the car is turned 90 degrees. The distance from the axis of the hinge pin to the inner axis of the cradle is such that when the cradle is at the highest point of travel, the material must drop three or four feet before it strikes the apron. This results in considerable breakage, which has heretofore been regarded as inevitable, particularly as it has been necessary to place the apron considerably below the highest point of cradle movement, in order to provide sufficient clearance for the cradle during the tilting cycle. Such breakage is objectionable however, as it decreases the value of the material particularly if it happens to be coal.

The principal object of the present invention therefore is to provide an apparatus by means of which the drop from the cradle to the apron may be substantially eliminated. In addition, the present invention is directed toward a device, which may be easily incorporated in the construction of new car dumpers, and readily attached as an auxiliary device to existing car dumpers.

The preferred means for carrying out my invention is shown in the drawings, wherein Fig. 1 is a transverse section through a car dumper showing the position of the cradle just before it reaches the highest point in the elevating movement; Fig. 2 is a section taken on the line 2—2 in Fig. 1; Fig. 3 is a plan view of the auxiliary apron, which forms part of this invention; Fig. 4 is a section taken on an enlarged scale on the line 4—4 in Fig. 3; Fig. 5 is a transverse sectional view similar to that shown in Fig. 1 and illustrates in full lines the position of the cradle at the highest point of the elevating movement, and shows in broken lines, the relationship of the cradle to the auxiliary apron when the cradle has been turned substantially ninety degrees, and Fig. 6 is a similar view showing the position of the parts when the cradle has been turned about one hundred thirty five degrees.

The car dumper, on which my invention is shown as the elevating type, wherein 10 designates the usual frame, and 11 the cradle, which is adapted to be elevated along the frame in the customary way. The 55 cradle is shown as having a platen 12, which is movable transversely thereof, and as having a car 13 in position upon the platen. Hinge pins 14 are shown on the frame, while cooperating sockets are indicated at 15 on the cradle. An apron which is normally used on present car dumpers is shown at 16, while the customary pan is indicated at 17. The upper edge of the apron terminates below the axis of the hinge pin in order to 60 provide adequate clearance for the top edge 18 of the cradle at the extreme forward end of the tilting movement. In such position, it is obvious from an inspection of Fig. 5, that there is a considerable drop before the 65 material strikes the apron. In practice, this amounts to three or four feet.

My invention enables material to slide gradually from the car to the apron, and the result is accomplished by utilizing an apron 20, which moves with the cradle during the 70 tilting cycle. On new installations, the apron 20 can be used to the exclusion of the apron 16, but in old installations, where it is desired to use my invention with the least 75 possible expense, it is preferable to leave the present apron in place, and to permit the shiftable apron to move over the present one. The shiftable apron comprises a fabricated structure, having body plates 21, which are 80 placed end to end, and fastened together as by riveting operation through angles 22. If desired however, the connections may be bolted together, so as to facilitate handling 85 during transportation. Additional angles 90 23 are shown, as being disposed at spaced intervals between the angles 22, to reinforce the body plates. Wearing plates 24 may 95 then be riveted onto the body plates between the angles.

100

The shiftable apron is normally adapted to be held above the pan and to be engaged automatically by the cradle and moved with it during the tilting cycle. To this end, I have shown the apron 20, as having a shoulder 25, which may comprise an angle member that is fastened to the underside of the apron, and that extends longitudinally thereof. Such member is adapted to engage a shoulder 26 on the frame or other stationary part of the superstructure. On present car dumpers, such shoulders may comprise an angle member, which is fastened to the upper end of the apron 16.

To cause automatic engagement between the apron and the cradle, I have shown a plurality of spaced hinge pins 30, which are mounted in brackets 31 along the top of the cradle. Such pins are adapted to be engaged by hook shaped members 32, which are disposed along the upper edge of the apron and are adapted to register with the pins as the cradle moves upwardly. The position shown in Fig. 1 illustrates the position of a pin 30 with reference to a member 32 when the sockets 15 are approaching the hinge pins. Continued upward movement of the cradle will cause the pins 30 to slide along the apron until they reach the innermost ends of the sockets and the associated members 32. The apron will then be carried around with the cradle during the tilting cycle, as is shown by the broken lines 20a in Fig. 5, and by the full lines in Fig. 6. In Fig. 5, the position of the apron indicated at 20a is that which will be assumed by it when the cradle is turned ninety degrees. That shown in Fig. 6 illustrates the position of the apron when the cradle is turned one hundred thirty five degrees. To prevent the apron from falling, I have shown a cable 40, one end of which is anchored at 41 to the apron 20, and the other end at 42 to the apron 16.

When the cradle reaches the end of the return movement of the tilting cycle and starts downwardly, guided by the frame, the shoulder 25 engages the stop 26. This holds the apron in the position shown in Fig. 1 and permits the pins 30 to be automatically disengaged from the hooks 32. Thus, the cradle may be lowered to the level of the approach and run-off tracks, while the apron remains in position for engagement upon the next elevation of the cradle.

From the foregoing description, it is apparent that the use of a shiftable apron maintains a substantially continuous surface along which, the coal can slide from the car to the pan. Furthermore, the top of the apron is always in relatively close position to the upper edge of the cradle at all times during the tilting cycle. In addition, the apron is automatically engaged and dis-

engaged on the upward and downward movements respectively of the cradle.

Having thus described my invention, I claim:

1. In a car dumper, the combination with a frame, of a cradle adapted to be elevated and tilted therein, a hinge member mounted upon the cradle, a material conveying apron disposed within the frame and overhanging the path of travel of the cradle, and means on the apron adapted to be engaged and raised by the hinged member and held in cooperative contact therewith during the tilting movement of the cradle. 70

2. In a car dumper, the combination with a frame, of a cradle adapted to be elevated and tilted therein, a stop member mounted upon the frame, a hinge member mounted upon the cradle, a material conveying apron disposed within the frame and carrying a second stop member and a second hinge member, said apron being supported during the tilting cycle on the cradle by cooperation of the two hinge members and supported at other times on the frame by co-operation of the two stop members. 80

3. In a car dumper, the combination with a cradle adapted for both vertical and tilting movement, of an apron having a downwardly facing shoulder adjacent the upper end thereof, means on the cradle for automatically engaging the shoulder at the start of the tilting cycle, and for holding the apron in pivotal relationship to the cradle during the tilting cycle, said apron being disconnected from the cradle by the downward vertical movement of the cradle away from said shoulder at the end of the tilting cycle. 90

In testimony whereof, I hereunto affix my signature. 100
